(57) **CLAIM**

What is claimed is the ornamental design for a valve seat, as shown and described.

DESCRIPTION

FIG. 1 is a perspective view of a valve seat comprising a first component positioned within a second component, where the first component can be fabricated from a carbide and the second component can be fabricated from steel;

FIG. 2 is a front view of the valve seat of FIG. 1;

FIG. 3 is a rear view of the valve seat of FIG. 1;

FIG. 4 is a left side view of the valve seat of FIG. 1;

FIG. 5 is a right side view of the valve seat of FIG. 1;

FIG. 6 is a top view of the valve seat of FIG. 1;

FIG. 7 is a bottom view of the valve seat of FIG. 1;

FIG. 8 is an exploded perspective view of the valve seat of FIG. 1; and,

FIG. 9 is a cross-sectional view of the valve seat of FIG. 1 taken along the line 9-9 as illustrated in FIG. 6.
